UNITED STATES PATENT OFFICE.

ALBERT THODE, OF HAMBURG, GERMANY.

LINE-INTERRUPTER FOR ELECTRIC RAILWAYS.

No. 904,902.

Specification of Letters Patent.

Patented Nov. 24, 1908.

Application filed July 8, 1908. Serial No. 442,514.

To all whom it may concern:

Be it known that I, ALBERT THODE, engineer, a subject of the Kingdom of Prussia, residing in Hamburg, in the Kingdom of Prussia, German Empire, Kaiser Wilhelmstrasse 20-26, have invented certain new and useful Improvements in Line-Interrupters for Electric Railways, of which the following is a specification.

10 The present invention relates to electric railway conductors and an important object is to provide an improved line interrupter for the same.

When constructing line interrupters for electric railway conductors there is a certain difficulty to be overcome inasmuch as the insulator which is to be inserted in the line has to take up the draft of the wires on the one hand, and on the other hand is also subjected to the pressure of the current collector which is directed vertically upwards. Having regard to the draft which is to be taken up, the material must be as tough as possible, whereas again having regard to the resistance to the upwardly directed pressure of the collector it appears desirable to use a material which is as hard as possible.

30 Insulating materials which are at the same time tough and of sufficient tensile strength and which, on the other hand, are very hard are however unknown. For this reason, according to the present invention the arrangement is such that the real separating or dividing piece of the line interrupter consists 35 of a material which is very tough and has a high tensile strength, but at the same time the line interrupter is provided with insulating or insulated pieces of hard material which are so arranged that they raise the 40 current collector somewhat from the real separating piece and so take up the pressure of the former, whereas the separating piece has only to take up the draft of the wires and, if desired, serves as guide for the collector.

45 In order that the invention may be clearly understood, reference is made to the accompanying drawing, in which one embodiment is represented by way of example, and in

50 which:

Figure 1 is a side elevation of one form of the line interrupter, Fig. 2 a top plan view, the roof having been removed, Fig. 3 a vertical transverse section in the plane

55 *xy* in Fig. 1, and Fig. 4 a vertical transverse section in the plane *yy* in Fig. 1, the roof and some other parts not being shown. The form of the invention represented is intended for mixed working with trolleys and sliding bows. In Fig. 4, however, the devices which are used for working with sliding bows are not shown, for the sake of greater clearness.

60 The new line interrupter possesses a separating or dividing piece 1, the material of which is selected only with regard to tensile strength and ductility, but not with regard to hardness. The separating piece may consist of wood for example. The wires 2 are connected with the separating piece or insulator 1 in optional known manner, according to the drawing by the forks 3.

65 Pieces 5 of porcelain are attached by means of bolts 4 laterally of the separating piece 1. The bottom faces of these pieces 75 of porcelain are situated so that the flanges of a trolley traveling under the interrupter run onto these bottom faces, so that the groove of the trolley is raised somewhat from the separating piece 1. The latter 80 then only serves in addition for guiding the trolley laterally, whereas the upwardly directed pressure of the collector is taken up by the pieces 5 of porcelain, thus by a material which is selected only with regard to its hardness, but not with regard to tensile 85 strength. The flanges of the trolley run onto the pieces of porcelain by means of metallic guides 6 which are attached to the 90 separating piece 1.

95 If the line interrupter is to be employed for use with sliding bows also, plates 7 are attached to the pieces 5 of porcelain, preferably by bolts 4. The bottom edges of these plates 7 are situated somewhat lower than those of the dividing piece 1. Thus they lift the bow, which is passing the interrupter, from the dividing piece 1, so that in this case also the latter can be selected 100 ductile and relatively soft, since the upwardly directed pressure of the bow is taken up by the plates 7 which on their part are made of a hard material. According to the herein described constructional form, metal is used as the material for these plates, and the plates are attached to the line interrupter insulated from the overhead wires. It is to be understood that other insulating 105

material corresponding to the above mentioned requirements may also be employed instead of a metal.

What I claim as my invention and desire to secure by Letters Patent is:

5. 1. In a line interrupter of the character described, the combination with an insulator having wires attached to the same, of insulators consisting of hard material arranged laterally on the former insulator and adapted to raise a trolley passing under the same from the former insulator.
10. 2. In a line interrupter of the character described, the combination with an insulator having wires attached to the same, of porcelain insulators attached one on each side of the former insulator and adapted to raise a trolley passing under the same from the former insulator.
15. 3. In a line interrupter of the character described, the combination with an insulator having wires attached to the same, of plates

attached laterally of said insulator and adapted to raise a sliding bow from the latter when the bow passes under the line 25 interrupter.

4. In a line interrupter of the character described, the combination with an insulator having wires attached to the same, of porcelain insulators arranged laterally on the former insulator and adapted to raise a trolley passing under the same from the former insulator, and plates attached laterally on the porcelain insulators and adapted to raise a sliding bow from the former insulator when the bow passes under the line 30 interrupter, substantially as shown.

In witness whereof I have hereunto signed my name this 24th day of June 1908 in the presence of two subscribing witnesses.

ALBERT THODE.
